UNITED STATES PATENT OFFICE

DAVID S. BAKER, OF GREENWICH, CONNECTICUT.

DRYING APPARATUS.

Application filed July 24, 1919, Serial No. 312,920. Renewed February 5, 1923.

To all whom it may concern:

Be it known that I, DAVID S. BAKER, a citizen of the United States, residing at Greenwich, county of Fairfield, and State of Connecticut, have invented a certain new and useful Drying Apparatus, of which the following is a specification.

This invention is a drying apparatus adapted for use upon, or in connection with, 10 different materials and manufactured products.

The object is to control the circulation of a gaseous drying medium so that it flows into contact repeatedly with the material or 15 product under treatment during transit of said material or product within a drying chamber, whereby the exchange of heat for moisture is effected under conditions assuring rapidity of drying with economy of 20 operation.

Generally stated, an apparatus of my invention embodies a drying chamber, a conveyor positioned for carrying the material or product within said chamber, a plurality 25 of relatively stationary deflectors so positioned with reference to the walls of the chamber as to produce compartments adjacent the path of said conveyor, baffles movable with said conveyor, and means for circulating a drying medium, usually preheated air, the direction of flow of which drying medium is controlled by the stationary deflectors and by the moving baffles so as to 30 attain multiple contact of said drying medium with the load (material or products) 35 in transit within the drying chamber.

A salient feature of the invention is the relation between the moving baffles and the deflectors adjacent thereto so that at no point 40 in the travel of the conveyor is there a free open space directly between one compartment and another compartment or compartments adjacent thereto, as a result of which the drying medium is controlled and directed 45 to flow in a zigzag path and transversely to the path of the conveyor and within the spaces intermediate the moving baffles. The described construction and organization so controls the flow of the drying medium that 50 it is brought into contact repeatedly with the load on the conveyor, thus attaining efficiency and economy of operation.

Other functions and advantages of the invention will appear from the following description taken in connection with the draw-

ings, the latter illustrating different constructional forms of the invention, and wherein—

Fig. 1 is a horizontal section through a drying chamber, illustrating in plan a traveling conveyor and a succession of moving baffles, the same constituting a drying apparatus embodying this invention. 60

Fig. 2 is a vertical longitudinal sectional elevation of the apparatus shown in Fig. 1. 65

Fig. 3 is a vertical transverse section in the plane of the dotted line 3—3 of Fig. 2.

Fig. 4 is a detail illustrating one means for the attachment of a baffle to a part of the conveyor. 70

Figs. 5, 6 and 6^a are views of another form of the apparatus wherein an overhead trolley conveyor is employed for carrying the load and imparting movement to the baffles; said Fig. 5 being a longitudinal sectional elevation, whereas Fig. 6 is a cross section, and Fig. 6^a is a detail of a form of double-roller trolley. 75

Fig. 7 is a longitudinal sectional elevation, and Fig. 8 is a cross section on the line 8—8, of still another form of apparatus embodying the invention. 80

Fig. 9 is a view, partly in longitudinal section and partly in elevation, of a form of apparatus adapted for drying coated manufactured products, such as automobile bodies. 85

The apparatus illustrated in Figs. 1 to 4 inclusive will first be described, referring to which A is a drying chamber of desired longitudinal and cross sectional dimensions; 90 said chamber may be a tunnel, or any other construction suitable for the purpose.

Within said chamber A is positioned a conveyor B, to which movement is imparted continuously or intermittently, as desired. 95 Said conveyor is or may be of any appropriate form. As shown it is an endless apron or belt, the loading and delivery end portions of which are exteriorly to the drying chamber. The end portions of said conveyor are 100 supported by shafts or drums b b'; it is shown as running over idlers b² positioned within the chamber A, and its idle run or lead is below said chamber.

Within the limits of the chamber are stationary deflectors C C'; the deflectors C extending inwardly from one wall, as c, of the chamber A, whereas the other deflectors C' extend inwardly from the other wall, c', of said chamber. The deflectors C on one side 110

of the chamber are spaced relatively to each other to provide adjacent circulating compartments D in the corresponding side of chamber A. Similarly, deflectors C' are spaced relatively to each other to produce other circulating compartments D' on the corresponding side of the drying chamber.

According to this invention the deflectors C in one series are in alternate or staggered relation to the corresponding deflectors C' in the other series, and further, each deflector is of a width in horizontal cross section equal substantially to the interval between two adjacent baffles on the endless conveyor, as will more fully appear presently.

It is apparent that the number of deflectors C C' and compartments D D' is not material, the number being dependent in a measure upon the longitudinal dimensions of the drying chamber and dependent, also, upon the number of times it is or may become desirable to direct the course of circulation of the drying medium across the path of movement of the conveyor and its load. As shown, the deflectors extend vertically within the drying chamber, and said deflectors are unitary with the walls c c' of said chamber; but the particular form of the deflectors is not material.

E are the movable baffles, the same being carried by the endless conveyor. As shown, each baffle is a flat imperforate plate—the height of which is equal substantially to the space between the top of the chamber and the upper run of the conveyor, whereas the width of said baffle is equal substantially to the space between the deflectors C C' in the opposite walls, see Fig. 3. Said baffles are attached fixedly to the conveyor in a suitable manner; as shown in Fig. 4 that edge of the baffle next to the conveyor is rigidly fastened to an angle iron e which latter is attached to the conveyor so that the baffles remain in permanent relation to the conveyor. The baffles are thus movable with the conveyor so as to travel therewith through the drying chamber and around the drums b b'.

In my apparatus the baffles are spaced relatively to each other, the interval between two adjacent baffles being equal substantially to, or being slightly less than, the width of the individual deflectors C or C'.

Means are provided for supplying a drying medium to the chamber A. It is usual to employ air as the drying medium, although furnace gases, or other aeriform fluid, may be utilized dependent upon the temperature desired and the character or nature of the substance or product to be dried. Air is circulated by means of a fan or blower, the air being usually preheated to a desired temperature, and being supplied by a flue or duct, the point of inlet be-

ing indicated at f in chamber D', see Fig. 1, whence the air circulates in the direction indicated by the arrows in Fig. 1. It has not been considered necessary to illustrate the blower, the preheater, or the air duct, for the reason that such adjuncts are usual in the drier art.

Within the compartments D D' are positioned boosters or reheaters F F' of any appropriate character. Said boosters are supplied with a desirable heating agent, such as steam, either live or superheated, hot air, furnace gases, or electric energy, or other agent. The boosters are shown as steam coils, extending lengthwise of the chambers D D', and supplied with steam from pipes or mains f', the latter having suitable stop cocks f² for controlling and regulating the flow of the heating agent.

The operation is as follows:—Steam is supplied to the boosters; the conveyor is set in motion, and air heated to a desired temperature is blown into the chamber. The material or product to be dried is supplied in any desired manner to the conveyor, being deposited thereupon in the spaces between the baffles, and said material or product is carried into and through the chamber A by the travel of the conveyor. The drying medium flows from one chamber D' and in one direction across the conveyor and between certain of the baffles E; enters one chamber D and is directed by the first deflector C to flow in an opposite direction across the conveyor and between certain other baffles E; enters the next chamber D' and is deflected by the second baffles C' so as to again reverse the direction of flow in a manner to again send it across the conveyor and between still other baffles E thereon, and so on throughout the length of the drying chamber. Conveyor B and baffles E travel within chamber A, preferably with a continuous movement, although such motion may be intermittent; but the relation of baffles E to deflectors C C' is such that at all times one or more of the baffles E are in register with deflectors C C'; in other words, at no period in the movement of the conveyor and the baffles does there exist a condition wherein a baffle or baffles are out of register with the deflectors C C', hence at no time is there free communication between compartments D D or D D' on one side or the other of the drying chamber. The moving baffles thus cooperate with the deflectors to cut off the direct flow of the drying medium in a straight course within the drying chamber, but on the contrary, said moving baffles and stationary deflectors cooperate to the end that the drying medium is compelled to flow back and forth within the drying chamber, or from one side thereof to the other, so that said drying medium circulates

transversely across the path of the conveyor,

through the spaces between the spaced baffles thereon, and into contact with the material or product constituting the load imposed upon the conveyor. The flow of the drying medium within the compartments D D' results in contact with the boosters, by which said medium is reheated to a desired temperature with a view to restoring to the drying medium the heat units extracted therefrom by contact with the moist material in effecting the exchange of heat for moisture, and thus the drying medium flows into contact alternately with the material or product and with the boosters, the latter acting, in the intervals between the successive contacts of said drying medium with the material, to reheat said drying medium in a manner to maintain the same at an uniform temperature, or even to an increased temperature, with a view to attaining efficiency in the drying operation and economy in the consumption of the heating agent for the boosters or reheaters.

In the constructional form of apparatus shown in Figs. 5, 6 and 6^a, the drying chamber A, the deflectors C C', the baffles E', and the boosters F F' are in a general way similar to the apparatus hereinbefore described with the object in view of controlling and directing the circulation of a drying medium in a back and forth direction transversely to the path of movement of a traveling conveyor. Said apparatus, however, embodies an overhead conveyor from which the load (products or material to be dried) and the baffles are suspended so as to be movable within the drying chamber. The roof or top a of the drying chamber is provided with a channel a', in which is positioned an overhead track or runway, shown in Fig. 6^a as consisting of a plurality of channel irons b³ b³, arranged one below the other. The moving conveyor consists of double chains B' having rollers b⁴ adapted to travel upon the channel irons of said track or runway; although it will be understood that a single channel iron and a single conveyor chain may be used, and, further, that any desired form of conveyor may be substituted for the particular conveyor herein shown.

Said overhead conveyor is adapted to carry the product to be dried in a suspended relation to the top of the drying chamber, for which purpose said conveyor is shown as being provided with depending hooks g on which are hung the product to be dried, see Fig. 5.

The moving baffles E' are suspended from the overhead conveyor, each baffle comprising a flat imperforate member the width and height of which are equal substantially to the width and depth of the chamber, see Fig. 6. Each baffle is attached to, or connected with, the overhead conveyor by

suitable means; as shown, a yoke shaped bar h is fastened to the baffle and connected with the axles of the rollers b⁴ for the double chain constituting the overhead conveyor. The baffles are thus suspended from the conveyor for movement within the drying chamber, and said baffles are so related to the walls of the chamber that they are normally at a right angle to the plane of said walls, whereby the baffles cannot be shifted by the flow and contact of the drying medium out of their desired positions relatively to the chamber. The overhead conveyor runs out of and into the drying chamber so that the load can be removed therefrom and connected therewith, the movement of said conveyor being continuous or intermittent, but the travel of said conveyor and the suspended baffles within the chamber exposes the suspended load to the action of the drying medium, the latter flowing back and forth within said chamber and in a path transversely to the conveyor and between the baffles thereon. The drying medium flowing into contact repeatedly with the product exchanges heat for moisture, and said drying medium is reheated by contact with the boosters for maintaining said medium in a desired condition and at a required temperature.

In Figs. 7 and 8 there is shown a constructional form of drier for rapidly loading and unloading flow materials usually stored in bulk condition, provision being made for the automatic feed of said flow material to a movable conveyor. The drying chamber A is a comparatively shallow elongated structure of desired cross sectional dimensions, the walls of said chamber being provided with deflectors as hereinbefore described, one series of which being indicated at C, and the said deflectors being relatively spaced along the opposing walls to produce circulating chambers, certain of which are indicated at D, which chambers contain the boosters or reheaters F and F', all as hereinbefore described. Within said chamber A moves the endless conveyor B² and the baffles E², said conveyor being supported and driven by drums b b' and the loading and delivery end portions of said conveyor being extended beyond the drying chamber. The baffles E² extend at a right angle to the conveyor, the dimensions of each baffle being proportioned to the interior cross sectional dimensions of the drying chamber, said baffles being attached fixedly to said conveyor by appropriate means.

Positioned over the loading end of the conveyor is a hopper G for containing the loose material in bulk. The bottom of said hopper is provided with suitable force feed means, the same being shown as rollers H positioned in the outlet throat g² of the hopper and said rollers being operated by ap-

propriate means, shown as a belt h^2 driven from the shaft or drum b , said rollers being operated at the required speed for effecting the delivery of a desired batch of the flow material from the hopper in a manner to deposit said material upon the conveyor and in the spaces or pockets existing between the adjacent baffles. Below the delivery end of the conveyor is a receptacle G' into which the dried material is dumped by the movement of said conveyor around the drum b' at the delivery end. The material is supplied in batches automatically to the conveyor upon which it is confined in separated masses by the baffles, and said conveyor carries the material within the drying chambers wherein the material is subjected to evaporation by the flow of the drying medium transversely across the path of said conveyor, said medium circulating as hereinbefore described and being reheated by contact with the boosters.

An apparatus for drying manufactured products of large dimensions is shown partly in Fig. 9, the same being constructed for operation in accordance with this invention. Within the drying chamber A operates an endless carrier B of a form adapted to carry the product to be dried, the same being depicted as an enameled automobile body, although it is apparent that the apparatus is or may be constructed for the treatment of other large objects. The drying chamber contains the deflectors C C', compartments D D', and boosters F F', all as hereinbefore described. Conveyor B is equipped with baffles E³ spaced with respect to each other for cooperation with deflectors D D' in the side walls of the chamber A. In this instance the baffles are detachably fitted to, or connected with, the conveyor so that said baffles are to be placed upon the conveyor at or before its entry into the drying chamber, and as the conveyor moves around the drum b' at the delivery end the baffles drop off said conveyor, the return lead or run of said conveyor being empty. It is apparent that any suitable means may be employed for retaining the baffles in the desired relation to the load-carrying run or lead of said conveyor, but as one means for this purpose there is shown in Fig. 9 a pair of parallel cleats i, said cleats being fixed to the conveyor and the cleats of each pair being in such relation that the baffle engages frictionally therewith and to such an extent as to remain in an upright position during the travel of the carrier and its load within the drying chamber.

Although I have described my invention as especially useful in connection with the operation of drying materials or substances, it is apparent that said apparatus is equally useful in the operation of exposing ma-

terials to heat for the purpose of conducting analogous operations on said materials, as e. g. baking coatings of materials applied to manufactured products.

Having thus fully described the invention, what I claim as new and desire to secure by Letters Patent is:

1. A drier embodying a chamber, means for transporting within said chamber the material to be treated, deflectors positioned on opposite walls of said chamber, and baffles movable within said chamber, the interval between two of said baffles being equal substantially to the length of one deflector.

2. A drier embodying a chamber, means for transporting within said chamber the material to be treated, deflectors positioned within said chamber at the respective sides of the path of the material-transporting means, the deflectors on one side being in alternate relation to the deflectors on the other side of said path, and baffles movable concurrently with said material-transporting means, the intervals between each two baffles being equal approximately to the length of one of said deflectors.

3. A drier embodying a chamber, an endless conveyor extending lengthwise within the chamber substantially continuously thereof, deflectors positioned within the chamber and at the respective sides of the path of said conveyor, the deflectors at one side of the conveyor path being in alternate relation to the deflectors at the other side of said path, and baffles movable concurrently with said conveyor, the interval between each two baffles being equal substantially to the length of one deflector.

4. A drier embodying a chamber, an endless conveyor extending lengthwise within the chamber substantially continuously thereof, deflectors positioned within the chamber and at the respective sides of the path of said conveyor, the deflectors at one side of the conveyor path being in alternate relation to the deflectors at the other side of said path, and baffles carried by said conveyor and movable therewith, the interval between each two baffles being equal substantially to the length of one deflector.

5. A drier embodying a chamber, an endless conveyor extending lengthwise within said chamber, deflectors positioned within said chamber and at the respective sides of the path of the conveyor therein, the deflectors at each side of said conveyor path being relatively spaced to produce heater-chambers, baffles movable concurrently with said conveyor, the interval between two adjacent baffles being equal substantially to the length of one deflector and said baffles being spaced to the heater chambers to provide a plurality of flow channels from the heater chambers on one side to the heater

chambers on the opposite side of the conveyor path, and boosters within said heating chambers.

6. A drier embodying a chamber, an endless conveyor extending within said chamber lengthwise thereof, a plurality of deflectors within said chamber, there being a number of said deflectors at each side of the conveyor path and said deflectors being relatively spaced to produce at the sides of the conveyor path a number of heater chambers, and baffles movable concurrently with said conveyor, said baffles being relatively spaced to produce separate flow channels extending crosswise of the conveyor and said channels having free communication with said heater-chambers, and boosters positioned within said heater chambers.

7. A drier embodying a chamber, an endless conveyor operable substantially therein, deflectors positioned at the respective sides of the path of said conveyor, said deflectors being spaced with respect to heater chambers at opposite sides of the conveyor path, and baffles movable concurrently with said conveyor, said baffles being relatively spaced to produce flow channels crosswise of the conveyor, there being a plurality of said baffles between adjacent deflectors positioned at the respective sides of the conveyor path, and boosters within the heater chambers.

8. A drier embodying a chamber, an endless conveyor operable within said chamber, deflectors positioned within said chamber and at the respective sides of the conveyor path, baffles carried by said conveyor and detachable therefrom, the interval between two adjacent baffles being equal substantially to the length of one deflector, and boosters at the respective sides of the conveyor path.

9. A drier embodying a chamber, a conveyor movable relatively thereto, a succession of baffles movable with said conveyor, each baffle being equal in area substantially to the cross sectional area of said chamber, and deflectors positioned at the opposite walls of said chamber, the width of each deflector being equal substantially to the intervals between the baffles.

10. A drier embodying a chamber, a conveyor movable relatively thereto, deflectors positioned at the respective sides of the chamber, the deflectors on each side of the chamber being relatively spaced to produce compartments adapted for the circulation therein of a drying medium, and baffles movable with said conveyor, the width of each deflector in horizontal cross section being equal substantially to the intervals between the baffles, and said deflectors and baffles cooperating to direct a drying medium in a zigzag course and transversely to the path of the conveyor.

11. In a drier, a chamber, means for moving material therein, a plurality of booster chambers, means separating booster chambers one from the other, and baffles movable within said first chamber, said baffles and 70 said separating means being mutually related for cutting off communication between adjacent booster chambers at any period in the movement of the baffles within said first named chamber.

12. In a drier, a chamber, means for moving material therein, a succession of booster chambers, means for separating adjacent booster chambers to cut off communication one from the other, and baffles movable 80 within the first chamber in a path intermediate the booster chambers, said baffles being in series intermediate the separating means for establishing individual channels within which a drying atmosphere is free 85 to flow in a transverse direction to the path of the material moving means.

13. In a drier, a chamber, means for moving material therein, a succession of booster chambers separated one from the other to 90 cut off communication between adjacent chambers, and baffles movable within the first chamber in a path intermediate said booster chambers, the dimensions of each baffle being equal substantially to the cross section of the first chamber and said baffles being in series with reference to each booster chamber for establishing individual channels for the flow of a drying atmosphere in a path transversely to the direction of movement of the material moving means. 95

14. In a drier, a longitudinal chamber, means for moving material therein, a succession of booster chambers, separators positioned intermediate adjacent booster chambers, and baffles movable within the longitudinal chamber and intermediate opposing booster chambers, said baffles being in series intermediate the ends of the booster chambers for establishing individual channels 110 within which a drying medium is free to flow transversely to the path of the material moving means, and said baffles and said separators being mutually related for cutting off communication between adjacent 115 booster chambers at any point in the movement of the baffles within said longitudinal chamber.

15. In a drying apparatus, a chamber, a plurality of booster chambers separated one 120 from the other, and a succession of elements movable within said chamber and performing the function of baffles for directing a drying atmosphere transversely with respect to said first chamber, said elements and the 125 booster chamber-separating means being mutually related for cutting off communication between adjacent booster chambers in any position of the elements within the first chamber. 130

16. In a drying apparatus, an elongated chamber, a plurality of booster chambers positioned at opposite sides of the medial line of said elongated chamber, the adjacent booster chambers being separated one from the other, and means within said elongated chamber and performing the function of baffles for directing a drying atmosphere in a path transversely with respect to said
- 10 elongated chamber, said baffle forming means being movable within said elongated chamber and co-operating with the booster-chamber separators for precluding the flow of the drying atmosphere from one booster
- 15 chamber to another.
17. In a drying apparatus, an elongated chamber, a plurality of separated booster chambers, and means movable within the elongated chamber and performing the function of baffles in directing the flow of a
- 20 drying atmosphere transversely within the elongated chamber, said baffle acting means and the booster-chamber separators being co-operable for precluding the flow of the drying atmosphere from one booster chamber to
- 25 an adjacent booster chamber during the movement of said baffle forming means.

In testimony whereof I have subscribed my name hereto.

DAVID S. BAKER.
